UNITED STATES PATENT OFFICE

2,010,294

BUILDING CONSTRUCTION

Harry L. Dovell, Chicago, Ill.

Application May 17, 1933, Serial No. 671,459

12 Claims. (Cl. 72—1)

This invention relates to an improved wall section and the method of using and assembling such section to form outer and inner walls, partitions, ceilings and the like for use in combination with an improved steel framework structure for buildings and the like.

It is an important object of this invention to provide an improved type of building section in the form of a flanged block open at either the front or the back and at the top and bottom, and including a closure plate or panel adapted to be secured to the block flanges after the block is mounted in position to close either the front or back of the block as the case may be.

15 It is also an object of this invention to provide an improved building unit designed for use in combination with steel frame structures, said unit comprising a hollow block and a closure panel constructed of durable, light-weight, waterproof and fireproof material having the inherent property of wood permitting the material to be cut or sawed and allowing nails, screws or other fastening means to be driven into the material for construction purposes and allowing the closure plates or panels to be fastened to the hollow blocks after the blocks have been mounted in position to form the major portion of an inner or outer wall or partition.

20 It is a further object of this invention to provide a building unit of an improved composition of matter which is light weight, waterproof and fireproof, and having certain of the inherent properties of wood permitting the material to be cut and sawed and allowing nails, screws and other fastening means to be driven into the material whereby the block portions of the unit may be mounted in position to form a wall or partition, one face of which is open and is adapted to be closed by means of closure plates or panels 25 forming part of the unit, permitting convenient mounting of pipes, conduits, wires and the like before the panels are secured in position and also permitting convenient and rapid access to the equipment enclosed by the wall section by the simple removal of the boards or panels from the block members.

25 It is a further object of this invention to provide a building unit comprising a grooved or channel-shaped block constructed of a composition material having certain of the inherent characteristics of wood, such block adapted to be mounted in position to partially surround or enclose equipment and frame members of a construction to permit the same to be substantially concealed by means of a closure board or panel

constructed of the same special material as the block and adapted to be fitted to the block and secured thereto by means of nails, screws or other fastening means whereby the open face of the block is removably closed to complete a wall section of the construction. 5

It is furthermore an object of this invention to provide improved building units consisting of channel-shaped blocks and closure panels therefore adapted to be used in combination with a building framework or the like to form outer and inner walls and partitions of the construction for enclosing the framework, the plumbing, piping, conduits, wiring and the like, said building units adapted to be secured in position by improved anchoring means, fastening units and connecting members. 15

It is another object of this invention to provide an improved wall and a method of constructing the same consisting of first mounting 20 a structural framework and the necessary piping, wiring, conduits and the like in position and then mounting a plurality of grooved or flanged building blocks in position to form open faced walls and partitions to partially enclose the 25 framework, piping, wiring, conduits and the like, and then completing the walls by closing the open sides thereof by means of panels or boards removably secured to the blocks to permit ready access to be had to the equipment enclosed in the 30 walls when necessary.

Another object of the invention is to provide a building consisting of a foundation and a framework supported thereon, with said framework having associated therewith adjacently positioned building units comprising open faced tiles or blocks and closure plates or panels for the same, said blocks adapted to be mounted in position adjacent one another to form open faced walls and partitions for the building permitting 40 piping, wiring, conduits and the like to be readily enclosed or installed in the open faced walls and partitions prior to the closing of the walls and partitions by means of the closure plates or panels which are adapted to be removably secured in staggered relation with respect to the blocks to close the walls and partitions. 45

It is an important object of this invention to provide an improved wall and method of construction without the use of laths, plaster and 50 the like, said wall being formed around a supporting framework and comprising channel-shaped or open faced tiles or blocks mounted in abutting or interfitting relation with one another to form an open faced wall, said blocks being 55

secured in position by improved tie rods, hangers, anchoring means and the like, said walls and partitions furthermore adapted to have the lower margins finished or enclosed by means of baseboards forming recesses or spaces for the reception of conduit, wiring and the like to permit the wiring and conduits to be directed up into the partitions and walls in desired locations by the simple removal of the baseboards.

10 Another important object of the invention is the provision of a building partition constructed of improved building units consisting of channel-shaped or grooved blocks having open faces adapted to be closed by means of closure panels 15 after the blocks are mounted in position to provide an open faced partition, said partition having the lower end thereof supported on an adjustable jack mechanism to permit the partitions to be conveniently adjusted to compensate for 20 variations in the distances between the floors and ceilings, said partitions having the additional advantage of being readily dismembered and the various sections or parts thereof reused to provide a partition in a different location or if desired permitting the entire partition to be conveniently shifted by removing the closure panels and releasing the upper and lower supports of the blocks.

30 Other and further important objects of this invention will be apparent from the disclosures in the specification and the accompanying drawings.

35 The invention (in a preferred form) is illustrated in the drawings and hereinafter more fully described.

On the drawings:

40 Figure 1 is a fragmentary perspective view of a building under construction illustrating the improved building units and the method of mounting the same in position associated with the building framework.

45 Figure 2 is an enlarged fragmentary perspective view of a portion of a wall constructed of improved open faced wall blocks and the closure panels therefor.

50 Figure 3 is a vertical detail sectional view taken through a wall and floor section and illustrating the method of securing the ceiling panels in position and also showing the associated relation 55 of the walls with the floor and ceiling.

Figure 4 is a fragmentary horizontal detail section through a corner of the building illustrating a wall having the open faced building blocks disposed on the inside and the closure panels on the outside.

60 Figure 5 illustrates another fragmentary horizontal section through intersecting walls of the building illustrating the positioning of a soil stack enclosed by a pair of oppositely directed abutting blocks.

65 Figure 6 illustrates a fragmentary horizontal sectional view of the building taken through an I-beam column or upright illustrating a channel-shaped block for enclosing the inner portion of the I-beam column.

70 Figure 7 is another fragmentary horizontal sectional view taken through a corner of the building and illustrating a modified form of corner structure employing blocks, the outer surfaces of the outer flanges of which are plain.

75 Figure 8 is a fragmentary elevational view of the abutting upper and lower ends of two vertically aligned walls with portions of the wall closure plates or panels broken away to illustrate the connecting or anchor rod construction at the

floor line for connecting adjacent blocks together.

Figure 9 is a fragmentary vertical detail section taken on line IX-IX of Figure 8 illustrating the means for supporting and anchoring the wall blocks to a base, foundation or floor, and to the end of an intermediate floor.

Figure 10 is a fragmentary vertical detail section through one story of a building illustrating a knockdown or movable type of adjustable partition and the means for removably securing the same in position and adjusting the partition to compensate for variations in room height.

Figure 11 is a vertical detail section taken on line XI-XI of Figure 10.

As shown on the drawings.

As clearly illustrated in Figure 1, the reference numeral 1 indicates a basement floor beneath the level of a ground floor 2. Supported on the basement floor 1 at required intervals are column foundation pedestals 3. Also supported on the basement floor 1 and upon the ground floor 2 are foundation walls 4 and 5. Supported on the foundation pedestals 3 and upon the foundation walls 4 and 5 is a steel structure or framework comprising columns 6 having secured or supported thereon cantilever floor sections 7. The vertical columns 6 and the cantilever floor sections 7 form column units having the adjacent column units connected by means of connecting floor sections 8. The connecting floor sections 8 on opposite sides of a room are connected by a main floor section consisting of adjacently positioned and connected inverted channel sections 9.

The entire framework is constructed of metal comprising the cantilever column units and the connecting metal floor unit. The metal framework is first completely mounted in position on the foundation supports 3, 4 and 5. After the metal framework has been assembled upon the foundation, the plumbing pipes 10, soil pipes 21, electric wiring, conduits and other similar equipment may be conveniently mounted in position supported by the weight carrying framework. The upper floor sections 8 and 9 and the upper cantilever platforms 7 form a metal roof section. The metal columns 6 are provided with the cantilever platforms 7 secured thereto and spaced one above the other a distance depending upon the height of the rooms of the building. The floor sections as well as the column units are adapted to be assembled as complete units at the factory and are shipped in sizes which may be conveniently handled at the building site.

One of the important features of the construction is the new and novel building units out of which the outer and inner walls and partitions of the building are adapted to be conveniently and rapidly built. Each of the building units 60 comprises a tile or block comprising, in one of its forms, a main plate or panel 11, side flanges 12 and 13, and an intermediate flange 14. As clearly illustrated in Figure 2, the flanges 12, 13 and 14 project from one surface of the plate or panel 11 outwardly in parallel relation to form an open faced building tile or block of any desired length having the ends thereof in the form illustrated in Figure 2 open. The outer face of the side flange 12 is provided with a groove 15 while the outer face of the flange 13 is provided with a rib or tongue 16. This construction permits adjacently positioned blocks to interfit one another. In Figure 7 a modified form of building tile or block is illustrated consisting of a main plate or 75

panel 17, end flanges 18 and an intermediate flange 19. This type of block is also of the open face construction having plain outer surfaces for the end flanges. While the two forms of building blocks are illustrated as having three projecting flanges, it will of course be understood that any number of flanges may be provided.

Associated with the building tiles or blocks are closure plates or panels 20. The building tiles or blocks and the closure plates or panels therefor are constructed of an improved light weight, waterproof and fireproof composition having a number of the inherent properties of wood permitting the material to be cut or sawed and also permitting nails, screws or other fastening means to be driven into the material for mounting the blocks and panels in position to form wall structures for the building. The tiles or blocks and the closure plates or panels therefor are preferably provided in ceiling-height lengths or greater so that shorter lengths may be cut therefrom on the construction job as required. The material of which the building blocks and closure panels therefor are constructed is of light weight so that the long lengths of the blocks and panels may be readily handled by workmen. The particular material of which the blocks and panels might be constructed is similar to that known in the trade under the trade-mark "X-Ite" and is covered by United States patent to Lon Edward Welch, Patent No. 1,626,577, dated April 26, 1927.

As illustrated in Figure 1, the improved grooved or channel-shaped open faced building tiles or blocks constructed of the selected material referred to or of a similar material having the required characteristics hereinbefore referred to are preferably furnished in floor or story heights. The blocks are mounted adjacent one another in abutting relation with the first floor or lower blocks supported on the foundation walls while the upper story walls are formed by supporting the lower ends of the blocks on the upper ends of the lower blocks. Single channel blocks 22, such as illustrated in Figures 5 and 6, may be used in abutting pairs as shown in Figure 5 to surround or enclose the soil stack or pipe 21 or as illustrated in Figure 6 one of the single channel blocks 22 may be used to enclose one side of one of the framework columns 6. Window openings 23 and door opening 24 may be cut in the blocks or, where more convenient shorter lengths of the blocks may be used as illustrated in Figure 1 to provide the required window or door openings.

At the corners of the building hollow corner blocks 25 are provided, as illustrated in Figure 4, for enclosing the tubular steel corner columns 26 or any other type of corner columns which may be used in the framework. As also illustrated in Figure 4, a corner strip or panel 27 constructed of the special material is used to form a closure for the column and a connection between the end blocks of the walls.

Where a corner construction is provided, such as is illustrated in Figure 7, the end blocks of the walls are adapted to overlap and an angle cross-sectioned corner block or strip 28 is used against the side edges of which the closure plates or panels 20 are adapted to abut.

It will be noted that in figures, such as Figures 4 and 7, the improved building blocks are positioned to form the inner sides of the walls while the outer sides of the walls are formed by the closure plates or panels 20. In Figures 1 and 2 the construction is shown wherein the

building blocks are used to form the outer sides of the walls while the closure plates or panels 20 are used to form the finished inner walls of the construction. Either type of construction may be used depending upon the design or construction selected by the architect.

For the purpose of holding the adjacently positioned blocks tightly connected one to the other, the webs or flanges of the blocks are provided with openings near the upper and lower ends thereof for the reception of connecting or anchoring rods 29, the ends of which are threaded for the reception of washers 30 and nuts 31 which together with right and left sleeve nuts 32, connecting adjoining threaded ends of the connecting rods, afford an arrangement for rigidly holding adjacent building blocks fastened together.

As clearly illustrated in Figures 8 and 9, the floor members 9 have integrally formed or rigidly secured thereto outwardly projecting flanges 33 having openings therein at spaced intervals for the reception of hook bolts 34 having the hook ends thereof engaged over the lower set of anchoring rods 29 in a wall. This equipment permits the lower ends of the blocks to be anchored to the metal floor structure. Also engaged at spaced intervals on the outwardly projecting floor flange 33 are a plurality of bolts 35 which project through slots in angle-shaped anchoring clips 36 provided with notches 37 to permit the anchoring clips to engage over an anchoring rod 29 for holding the upper margin of a wall in proper position.

As illustrated in the lower portion of Figure 9, the lower margin of a wall is adapted to be anchored or secured to the foundation by means of T-head bolts 38 which are engaged in T-slots 39 provided in the foundation. The T-head bolts 38 are engaged through anchoring clips 36 having the notches 37 thereof engaged over one of the lower anchoring rods 29 thereby preventing the lower margin of a wall from being shifted or moved out of position.

The floors of the building construction, as illustrated in Figures 3, 9 and 10, are formed by laying a layer of insulation 40 upon the top surface of the metal framework floor formed by the members 7, 8 and 9. On top of the layer of floor insulation 40 the flooring 41 is placed.

The ceilings of the rooms of the building are also constructed out of the plates or panels 20 which are secured in position by nails or screws driven into blocks 42 or 43 which are constructed of the special material of which the building blocks 11 are constructed. As clearly illustrated in Figure 3, the ceiling supporting blocks 43 comprise a metal shell which is filled with the special material. The ceiling supporting blocks 42 and 43 are adjustably hung in position by means of hook bolts 34 which are hooked over supporting bolts 44 which are engaged through apertures provided in the downwardly projecting flanges of the metal floor sections 9.

As illustrated in Figure 3, a modified fastening device is shown whereby the lower margins of a wall may be secured to the floor. The wall support comprises a metal channel 45 which is bolted to the framework flooring 9. The side flanges of the channel 45 are provided with openings 46 at intervals to permit wiring, conduits and the like to be conducted upwardly into the wall. The upper margins of the side flanges of the channel 45 are bent outwardly and upwardly to provide supporting shoulders 47 to 75

provide seats for the lower end of the wall. Baseboards 48 of the special material rest on the flooring 41 and are secured to the wall by means of nails, screws, or other fastening means.

5 Also illustrated in Figure 3 is a modified form of building blocks 49 constructed similar to the blocks 11 with the added feature of having the ends formed with closure flanges or end pieces 50 to permit the ends of the blocks to be respectively nailed to the ceilings and floors. When desired, the upper corners of the rooms may be finished by means of molding strips 51 or, if desired, such molding strips may be nailed or secured to the upper margins of the walls.

10 15 Figure 10 illustrates a removable wall or partition adapted to be readily constructed in a building in such a manner that the various parts forming the partition may be readily dismembered and reused in a new location. The partition wall is constructed of the special blocks 11 and the closure plates or panels 20 which are supported in angle bars 52 which are connected by cross plates 53 forming part of a series of adjustable supporting jacks 54. The adjustable jacks 54 are supported in base channels 55 provided with openings to permit the same to be secured in a selected position on the floor 41. The side flanges of the base channels 55 are provided with threaded openings to removably receive retaining screws 56 for removably securing baseboards 57 in position on opposite sides of the lower portion of the wall to enclose the adjustable mechanism for raising or lowering the partition. By securing the baseboards to the base channels 55 it is not necessary to drive nails or screws through the baseboards into the partition wall. This arrangement obviates the formation of holes in the lower margin of the partition wall so that in case the wall is raised there will be no marred surfaces disclosed above the upper edges of the baseboards. The space below the partition wall in between the baseboards affords a storage space or compartment for conduits, wires, pipes and the like to which access may be readily had by the removal of one or both of the baseboards.

45 50 For the purpose of removably securing the upper end of the partition in place a Z-bar 58, one flange of which is secured to the ceiling by means of anchoring bolts 34, is provided. Mounted in the other horizontally positioned flange of the Z-bar 58 are a plurality of adjustable hook bolts 34, the hook ends of which are engaged around a connecting or anchoring rod 29 which connects the upper adjacently disposed ends of the building blocks 11 which form the major portion of the partition wall. The open faced partition wall formed by the blocks 11 which are supported on the adjustable supporting base and by the upper mechanisms supported on a ceiling is adapted to be closed by means of the closure plates or panels 20.

55 60 The seams or cracks between the blocks and panels forming the walls, partitions, ceilings and the like, are adapted to be closed when necessary by a mastic joint of the particular material of which the building blocks and panels are constructed. The particular kind of material of which the wall blocks and panels are constructed permits any desired finish to be provided for the exposed surfaces forming the walls so that when the building blocks and panels are in position, finished surfaces are provided. The novel construction described eliminates the use of wall laths, plaster and the like. It will also be under-

stood that the improved material may be colored as desired so that panels and blocks of desired colors may be used for producing rooms or outer walls of selected colors. The wall blocks and panels may furthermore have embossed or embedded designs formed in the exposed surfaces thereof so that decorative effects may be produced.

5 10 15 Referring to Figure 1, the building construction is adapted to use the upper metal floor framework section as a steel roof deck which is adapted to be covered with cork or other selected material 59 over which pairs of roofing material 60 are placed. The walls of the upper floor of the building construction are permitted to project a short distance above the roof to form a coping wall the upper ends of which are covered by cast coping tiles 61 constructed of the special material of which the building wall blocks and panels are constructed. The window openings 23 and the door openings 24 located as desired are adapted to have the window frames and door frame secured therein.

20 25 30 35 The improved building units consisting of the blocks 11 of special material and the closure panels or plates therefor are novel not only in that they are constructed of the special material having a number of the inherent characteristics of wood but said building units further permit the building blocks to be assembled and connected to form an open faced wall around the building frame members and around the conduits, pipes, wiring and the like, before it becomes necessary to close the walls by means of the closure plates or panels. This novel construction is new in the art of building and permits ready access to be had to the equipment within the open walls during the period of construction. The arrangement also permits convenient access to be had to the equipment within the walls after the building is completed by the simple removal of the required wall panels.

40 45 50 It will, of course, be understood that various details of construction may be varied through a wide range without departing from the principles of this invention and it is, therefore, not the purpose to limit the patent granted hereon otherwise than is necessitated by the scope of the appended claims.

I claim as my invention:

55 60 65 70 75 1. In a building construction, the combination with a structural framework, of a wall structure for use therewith for enclosing members of the framework, said wall structure comprising flanged open faced blocks positioned adjacent one another to form an open faced wall for partially enclosing members of the framework, adjustable means for securing the blocks in position, and wall panels removably secured to the blocks to close the open face of the wall and complete the enclosure of the framework part.

2. In a building construction, the combination with a structural framework, of walls for enclosing members of the framework, partitions in said building construction, means for adjusting the partitions, each of said walls and partitions comprising open faced blocks secured together in abutting relation to form an open faced wall or partition, and panels secured to the blocks to close the open face of each wall and partition.

3. A building wall structure comprising a framework, a plurality of open faced blocks secured together to form an open faced wall partially enclosing the framework, means within the wall for adjusting the same, and closure pan-

els secured to the wall structure to close the open face thereof to complete the enclosure of the framework.

4. A building wall structure comprising a plurality of channel cross-sectioned interfitting blocks forming an open faced wall section, adjustable means for removably supporting the wall section in position, and closure panels removably secured to said blocks to form a closure for the open face of the wall section.

5. A building wall structure comprising a plurality of interfitting open faced flanged blocks, means for securing the same in position to form an open faced wall, means for vertically adjusting the wall, and a plurality of panels removably secured to the wall in staggered relation with respect to the blocks to close the open face of the wall section.

6. A building wall comprising a plurality of adjacently positioned channel cross-sectioned blocks, means for holding the blocks connected one to another to form an open faced wall section, adjustable means for anchoring the upper and lower ends of said blocks in position to hold the open faced wall section in place, and closure panels for closing the open faced wall section.

7. In a building construction wherein a framework is supported on a foundation, the combination with a plurality of adjacently positioned open faced blocks, means for securing the blocks together to form an open faced wall partially enclosing members of the framework, means for anchoring and holding the open faced wall in place whereby conduits, wiring and the like may be mounted in position in the open face wall, and closure panels secured to the open face wall to close the same and complete the enclosing of the frame members and other equipment.

8. In a building construction wherein a metal framework is supported on a foundation, the combination with the walls, floors and ceilings of the building construction, of a demountable partition comprising a plurality of adjacently positioned open faced blocks, means for securing said blocks together to form an open faced wall section, an adjustable support for the wall section for raising or lowering the same, means for anchoring the upper end of the wall section to the ceiling, removable base members for the wall section for enclosing the adjustable supporting means for the wall section, and panel members removably secured to the open faced wall section, said partition being demountable for shifting and re-use of the partition parts in reassembling the partition in a different location.

9. In a building construction the combination

with a floor and ceiling thereof, of a demountable partition comprising a plurality of open faced blocks positioned adjacent one another, means for securing said blocks together to form an open faced partition wall, means for removably anchoring the upper end of the partition wall to the ceiling, adjustable supports for the lower end of the partition wall, panels removably secured to the open face of the partition wall, and baseboard members supported on the floor against opposite sides of the lower end of the partition to enclose the adjustable supports.

10. In a building construction of the class described a demountable partition for dividing room space, said partition comprising flanged open faced blocks positioned side by side in abutting relation, means for securing said blocks together to form an open faced wall section, means for anchoring the upper end of the wall section to a room ceiling, an adjustable support for supporting the lower end of the wall section on the floor of the room, closure panels removably secured to the wall section to close the open face thereof, said closure panels also supported on the adjustable support, and baseboards supported on the floor on opposite sides of the partition and secured to the adjustable support with the upper margins of the baseboards overlapping the lower margin of the partition without being secured thereto.

11. In a building construction of the class described, a demountable partition comprising an open faced wall, a closure for closing the open face of said wall, means for anchoring the upper end of the wall to a room ceiling, adjustable supports mounted on the floor beneath the partition and serving as a seat for the lower end of the open faced wall and the closure therefor, said adjustable supports holding the lower end of the partition spaced above the floor to afford a conduit and wire space beneath the partition, and baseboards supported on the floor on opposite sides of the partition, and secured to a portion of the adjustable supports to enclose the same with the upper margins of the baseboards having free contact with the opposite faces of the lower end of the partition.

12. In a building construction, a building unit comprising a base section, a wall section vertically adjustable therein, means in the base section for adjusting the wall section with respect to the base section, and adjustable anchor means in the wall section for holding the same in position after the adjustment thereof.

HARRY L. DOVELL.
